UNITED STATES PATENT OFFICE.

HENRY CLAYTON, OF DAYTON, OHIO, ASSIGNOR OF ONE-HALF TO
WILLIAM O. McCABE, OF SAME PLACE.

PUMP ATTACHMENT.

SPECIFICATION forming part of Letters Patent No. 256,125, dated April 11, 1882.

Application filed January 18, 1882. (No model.)

To all whom it may concern:

Be it known that I, HENRY CLAYTON, of Dayton, in the county of Montgomery and State of Ohio, have invented certain Improvements in Pump Attachments, of which the following is a specification.

My invention consists in a detachable strainer attachment of improved construction for pump-spouts, composed of a ring or band fitted to the end of the spout and provided with projecting lugs, and a cap or ring notched to lock over said lugs and provided with a strainer, as hereinafter more fully set forth, and in providing the attachment with a valve for the discharge of sediment, &c., as will be explained.

In the accompanying drawings, Figure 1 represents a perspective view of a pump-spout with my improved attachment applied; Fig. 2, a view with the strainer-cap detached, and Fig. 3 a vertical transverse section of the attachment.

The object of my invention is to provide a cheap and simple attachment which may be applied to the spouts of pumps in common use to prevent the escape of sediment or foreign matters of any kind from the spout to the receiving-vessel placed beneath it. With this end in view I construct the device as shown in the drawing, in which—

A represents a pump-spout; B, a ring or band, secured thereon by screws or otherwise; and C, a cap, provided with a strainer, *a*, of wire-gauze or other suitable material, and having notches *b* to receive and lock around lugs or projections *c* formed on the band B. As more clearly shown in Fig. 3, the band B is formed with an internal radial flange or plate, *d*, to fit against the end of the pump-spout, and perforated to receive the fastening-screws *e*, as shown. It is also preferably constructed to project in rear of said flange, as shown in said figure, in order that it may encircle and protect the end of the spout.

The cap C consists merely of an annular metal band, preferably having an inwardly-turned flange, *f*, to which the straining material is secured by soldering, by a wire or metal ring pressed in behind it, or in any other usual and convenient way. The cap is formed, as above stated, with notches or slots *b*, which are

shown of L shape, but which may be curved or inclined, said notches being made to permit the cap C to be pressed upon the band D until the edge of the cap passes the lugs or projections *e*, when, by turning the cap, it is caused to lock fast upon the band, as shown in Fig. 1.

For the purpose of removing any sediment which may collect within the spout or behind the strainer, the band is furnished with an outlet-valve, D, which is normally held closed by a spring, *g*, but which is provided with a thumb-piece or tail, *h*, by which it may be conveniently operated. When, therefore, sediment collects, it is only necessary to press upon the thumb-piece *h* and operate the pump for a moment, when all deposit will be washed out.

Should any injury occur to the strainer, or should it be desired at any time to remove it from the spout, it is only necessary to turn the cap C and draw it off.

It will be seen that by reason of the plate or flange *d* the ring or band B, and consequently the entire attachment, may be applied to pump-spouts of various sizes; and it will also be observed that the strainer-surface *a* is considerably larger than the opening in the plate or flange *d*, and consequently that a free outlet for the water is afforded, the larger area compensating for the retarding tendency of the strainer.

I am aware that a strainer has heretofore been applied to pump-spouts and provided with a trap or valve to catch and retain frogs, &c., as well as foreign matters; but I am not aware that any one has ever before constructed such a device as herein set forth, or that a strainer attachment has ever before been furnished with an outlet-valve to permit the removal of sediment while the attachment is in place.

I am aware that a valve-protector has been patented consisting of a case or vessel containing a screen or gauze diaphragm, and a blow-off-cock in rear thereof for blowing out sediment deposited, and this I do not claim.

Having thus described my invention, what I claim is—

1. The herein-described attachment for pump-spouts, consisting of the band B, pro-

vided with lugs or projections, and the cap C, having a strainer, *a*, and notched, as explained.

2. In combination, the spout A, the band E, constructed substantially as shown and described, whereby it is adapted to encircle the end of the spout, and strainer-cap C, applied substantially as shown and described.

3. In combination with a pump-spout and a strainer applied thereto, an outlet-valve in 10 rear of the strainer, whereby the sediment can be discharged without removing the strainer.

4. In combination with a pump-spout, a strainer attachment consisting of band or ring B, provided with valve D, and strainer-cap C, all constructed and arranged substantially as 15 shown and described.

HENRY CLAYTON.
